HOUSING FOR AUTOMATIC AEROSOL DISPENSER

William L. Soles, Toronto, Ontario, Canada, assignor to
Air Guard Control of Canada Limited, Toronto, Ontario, Canada

Filed Sept. 2, 1966, Ser. No. 3,694

Term of patent 14 years

(Cl. D52—2)

FIG. 1

FIG. 2

FIG. 3

FIG. 4

FIG. 1 is an isometric view of the instant housing for automatic aerosol dispenser particularly showing its top end, side and front panel;

FIG. 2 a front elevational view of the housing;

FIG. 3 an elevational view showing one side of the instant housing; the other side corresponding thereto, and

FIG. 4 a section along the line IV—IV of FIG. 2.

The rear of the housing is plain and unornamented.

I claim:

The ornamental design for a housing for automatic aerosol dispenser, substantially as shown and described.
